Patented July 27, 1920.

FIG. 1.

FIG. 2.

INVENTOR
FREDERICK FRYER WILKINS
By *John McNamee Jr.*
Atty.

UNITED STATES PATENT OFFICE.

FREDERICK FRYER WILKINS, OF WEST KILBURN, LONDON, ENGLAND, ASSIGNOR TO
BENJAMIN EDSALL JOHNSON, OF LONDON, ENGLAND.

LOCK OR BOLT FOR DOORS AND THE LIKE.

1,347,799.

Specification of Letters Patent. Patented July 27, 1920.

Application filed June 9, 1919. Serial No. 302,856.

To all whom it may concern:

Be it known that I, FREDERICK FRYER WILKINS, a subject of the King of Great Britain and Ireland, and a resident of West Kilburn, county of London, England, have invented a certain new and useful Improvement in Locks or Bolts for Doors and the like, of which the following is a specification.

10 This invention has reference to that type of lock or bolt for doors, casements and the like wherein no key is employed, the bolt proper being spring-controlled and operated in a casing by a simple slide action from the 15 exterior or the interior of such door, and in which there is embodied a means for locking the bolt in its outward position, consisting of an auxiliary bolt in the casing which may be slid up to and abut on the interior end 20 of the bolt, and which is retained in the locking position by giving it a partial turn, causing a knobbed spindle on the auxiliary bolt to enter a notch of a slot in the casing.

In the present invention the construction 25 is improved by inclosing the bolt action more completely to protect it from dust and the effects of the weather. The slots in which the knobbed spindles of the two bolts work are reduced to minimum dimensions and the 30 spring is concealed from view and is not exposed to injury from dust and damp.

A further improvement is also made in order to make the bolt action more reliable and to eliminate any risk of the coils of the 35 spring jamming against the inner ends of the two bolts, by making the main bolt tubular or hollow for a part of its length and prolonging the reduced end of the auxiliary bolt so that it is always contained in 40 the hollow of the main bolt and in correct alinement therewith. The spring thus surrounds the reduced portion of the auxiliary bolt, abutting against the shoulder thereon and also against the tubular end of the main 45 bolt.

In the accompanying sheet of drawings:—
Figure 1 is an elevation; and,

Fig. 2 is a plan, partly in section, of the improved lock.

50 Referring to the figures, *a* is the improved protecting casing secured to the door *b* and containing the bolt *c* with knobbed spindle *d*, and *e*, *e* are the reduced slots in the casing. *f* is the spring surrounding the reduced part *g* of the bolt *h*, which latter is

the auxiliary bolt with knobbed spindle *i* which slides in the slot *e* and by a partial turn up or down can be inserted into the notch *j*, thus locking the bolt *c* and preventing it from being drawn back, as its end 60 butts against the auxiliary bolt *h*, the reduced portion *g* sliding in the hollow *h'* of bolt *c*.

The back of the base plate *n* is preferably overlapped top and bottom by the edges of 65 the outer casing, so insuring the complete inclosure of the working elements.

To prevent the knobbed spindle *i* of the auxiliary bolt *h* contacting against and burring the end of the slot in the casing, the 70 back plate is inturned at *n'* so that the end *o* of the bolt *h* takes up any percussion caused by the spring *f*.

The opening *p* is closed by a cover plate *p'* adapted to the spindle on which the knob 75 *d* is mounted.

Having now described my invention, what I claim as new and desire to secure by Letters Patent of the United States is:—

1. A latch device including a casing having an opening, a main latch member slidable therein and having a socket in one end, a locking bolt arranged within the casing and having a reduced end portion adapted to fit in said socket of the main latch bolt, 80 a spring confined between the end of the main latch bolt and the shoulder formed at the junction of the reduced end portion of the locking bolt with the body thereof, and a handle carried by the body of the locking 85 bolt and coöperating with the opening in the casing to be held in locked position.

2. A latch device of the class described including a slotted casing, a main latch member and a locking bolt slidably arranged 90 within the casing, a spring interposed between said main latch and the locking bolt, and a handle projecting from the locking bolt and coöperating with a slot of the casing to hold the locking bolt in a fixed position when the main latch and locking bolt are relatively close together to lock the said main latch bolt against backward movement.

3. A latch device of the class described 105 including a casing having a substantially T-shaped slot, a main latch member slidable in one end of the casing, a locking bolt slidably in the opposite end of the casing, a spring between said latch and bolt, and a 110

handle carried by the bolt and projecting through the T-shaped slot of the casing, whereby when the same is positioned in the head of the T-shaped slot the bolt will be held in locking relation with reference to the latch.

4. A latch device of the class described including a casing having a longitudinal slot and also a T-shaped slot, a latch member 10 slidable in the casing and having a transversely disposed handle portion projecting through the longitudinal slot of the casing, said latch member also having a socket, a locking bolt slidably mounted in the other

end of the casing and having a reduced end 15 portion for engaging in the socket of the latch member, a spring surrounding the reduced end portion of the bolt and confined between the shoulder thereof and the end of the latch, and a handle projecting from 20 said bolt through the T-shaped slot whereby when the handle is in the head of said slot the reduced end portion of the bolt will be held in locking engagement with reference to the socket end of the latch.

In testimony whereof I have affixed my signature hereto this 21st day of May, 1919.

FREDERICK ERYER WILKINS.
